ELECTRONIC PHOTOFOLASH UNIT

Robert M. Hogue, 4425 W. Dunwood Road, Brown Deer, Wis. 53223, and Donald N. Emmerich, Glendale, Wis.; said Emmerich assignor to said Hogue

Continuation of design application Ser. No. 21,768, Mar. 6, 1970. This application July 12, 1971, Ser. No. 161,377

Term of patent 14 years

Int. Cl. D16—05

U.S. Cl. D61—1 F

FIG. 1 is a perspective view of an electronic photoflash unit showing our new design;

FIG. 2 is a side elevational view of FIG. 1, the opposite side being substantially a mirror image thereof;

FIG. 3 is a right side elevational view of FIG. 2;

FIG. 4 is a top plan view of FIG. 3; and

FIG. 5 is a bottom plan view of FIG. 3.

We claim:

The ornamental design for an electronic photoflash unit, as shown and described.
